UNITED STATES PATENT OFFICE.

EDWARD S. NOVAK, OF GLASSPORT, PENNSYLVANIA.

GAME-BOARD.

1,301,867.

Specification of Letters Patent. Patented Apr. 29, 1919.

Application filed June 14, 1918. Serial No. 240,006.

To all whom it may concern:

Be it known that I, EDWARD S. NOVAK, a citizen of the United States, residing at Glassport, in the county of Allegheny and 5 State of Pennsylvania, have invented new and useful Improvements in Game-Boards, of which the following is a specification.

This invention is an improved game apparatus for playing what I call a war game, 10 the object of the invention being to provide a game apparatus of this class which enables an interesting game to be played without skill on the part of the players, and in which the element of chance is at its maximum.

15 In the accompanying drawings:—

Figure 1 is a plan of a game apparatus constructed and arranged in accordance with my invention.

20 Fig. 2 is a sectional view of the same taken on the line 2—2 of Fig. 1.

Fig. 3 is a detail sectional view, showing the bar or disk throwing element.

In the embodiment of the invention here shown, a board 1 is provided which is round- 25 ed at one end as at 2 and which has a nar- rowed portion 3 at the other, the front end, and is also provided with a surrounding wall or flange 4. The board presents a runway 5 on the opposite sides of which are 30 spaced blocks 6, 7, 8, 9, 10, 11, as shown. At the rear end of the board is a field 12 which is here shown as divided into cross spaces 13, 14, 15, 16. Near the front end of the board and arranged in line with the center 35 of the runway 5 is a spring bar or disk throwing element 17 which may be bent back by the finger and when released caused to throw a disk 18 along the runway 5.

I also provide game pieces of different 40 point values, said game pieces being here shown as flags 19, cannon 20, ammunition piles 21 and soldiers 22, each of which may be made of wood, tin or any other suitable material, and in all twelve the said pieces 20, 45 21, 22 being provided which are differently colored, six of the pieces that is to say, two of the cannon, two of the ammunition piles and two of the soldiers, being of one color, such for instance, gray, and the other cor-

responding pieces being of another color, 50 such for instance, blue, and to respectively indicate German and French. Two of the flag pieces 19 are provided, one the German flag and the other the French flag to correspond with the other pieces. The board is 55 provided with openings in which the flag staffs may be mounted as at 23.

The game is played as follows: Players choose sides and each player places his flag appropriately on the board. The board being clear, the players shoot the disk successively. The first object of each player is to assemble his army represented by the pieces 20, 21, 22. When he shoots the disk, if the same falls, say, in the space 14 of the field 60 and between the lines such player then is entitled to take a cannon piece 20 and to place the same on one of the blocks on his side of the board. If the disk stops on one of the lines the player is entitled to nothing. 65 If the disk stops in the space 13 the player is entitled to a soldier figure 22. If the disk stops in the space 15 the player is entitled to an ammunition figure 21. The object of each player is to get all his pieces in the 70 field and to prevent his opponent from doing so. After a player has gotten all of his pieces in the field each succeeding shoot which he makes entitles him to take one of the pieces of his opponent from the field, 75 according to the point at which the disk stops. That is to say, if the disk stops in the space 13, he takes one of his opponent's soldiers 22. If the disk stops in the space 14, he takes one of his opponent's cannon 20. 80 If the disk stops in the space 15, he takes one of his opponent's ammunition piles 21. If the disk stops on any of the lines between the spaces, he takes nothing. 85

The object of the game is to get all of the 90 opponent's pieces.

Having thus described my invention, I claim:—

1. The herein described game apparatus comprising a board having a field at one end 95 divided into spaces and provided at the opposite end with a disk projecting device, the board being also provided at opposite sides

with game piece receiving spaces; a disk, and game pieces for arrangement in the said game piece spaces.

2. The herein described game apparatus comprising a board having a field at one end divided into spaces and provided at the opposite end with a disk projecting device, the board being also provided at opposite

sides with game piece receiving spaces; a disk, and game pieces for arrangement in the said game piece spaces, said game pieces comprising flags, cannon, ammunition piles and soldiers.

In testimony whereof I affix my signature.

EDWARD S. NOVAK.
